Primary Examiner — T Chase Nelson*Assistant Examiner* — Sydney Margaret Parsley(74) *Attorney, Agent, or Firm* — Jacox, Meckstroth & Jenkins(57) **CLAIM**

The ornamental design for a beam, as shown and described.

DESCRIPTION

FIG. 1 is an isometric view of the beam showing my new design;

FIG. 2 is a front elevation view of the beam of FIG. 1;

FIG. 3 is a rear elevation view of the beam of FIG. 1;

FIG. 4 is a left side elevation view of the beam of FIG. 1;

FIG. 5 is a right side elevation view of the beam of FIG. 1;

FIG. 6 is a top plan view of the beam of FIG. 1;

FIG. 7 is a bottom plan view of the beam of FIG. 1; and, FIG. 8 is an enlarged, fragmentary view of the two ends of the bottom of the beam shown in FIG. 7, the beam being shown in fragments for the purpose of enlargement.

The broken lines in the enlarged, fragmentary view of FIG. 8 are for the purpose of showing the boundaries of the fragmentary ends of the beam that is fully shown in FIG. 7. These boundaries are for the purpose of enlargement only and form no part of the claimed design.
